DESCRIPTION

FIG. 1 is a bottom plan view of the shoe sole embodying the new design;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a perspective view thereof.

The broken lines showing a shoe upper in FIGS. 2–6, illustrate environmental context only, and form no part of the claimed design.
